Primary Examiner—Alan P. Douglas*Assistant Examiner*—Deanna Fluegeman(74) *Attorney, Agent, or Firm*—Chernoff, Vilhauer, McClung & Stenzel, LLP(57) **CLAIM**

The ornamental design for a folded multipurpose hand tool, as shown and described.

DESCRIPTION

FIG. 1. is an isometric view from the upper right front of a folded multipurpose hand tool including my new design;

FIG. 2. is a top plan view thereof;

FIG. 3 is a right side elevational view thereof;

FIG. 4 is a left side elevational view thereof;

FIG. 5 is a bottom plan view thereof;

FIG. 6 is a front end elevational view thereof; and,

FIG. 7 is a rear end elevational view thereof.
